LEG UNIT

Robert J. Dottinger, Hawthorne, N.J., assignor to The Lehigh-Leopold Furniture Company, Burlington, Iowa, a corporation of Delaware

Continuation-in-part of design application Ser. No. 4,017, Sept. 26, 1966. This application Feb. 4, 1969, Ser. No. 15,615

Term of patent 14 years

Int. Cl. D6—01

U.S. Cl. D33—14

FIG. 1

FIG. 2

FIG. 3

FIG. 4

FIG. 5

FIG. 6

FIG. 8

FIG. 7

FIG. 9

FIG. 1 is a front perspective view of a leg unit embodying my new design;

FIG. 2 is a rear perspective view of the leg unit of FIG. 1;

FIG. 3 is a front view of the leg unit of FIG. 1;

FIG. 4 is a sectional view taken on line 4—4 of FIG. 1;

FIG. 5 is a front view of a modified form of leg unit embodying my new design;

FIG. 6 is a sectional view taken on line 6—6 of FIG. 5;

FIG. 7 is a front view of another modified form of leg unit embodying my new design;

FIG. 8 is a sectional view taken on line 8—8 of FIG. 7; and

FIG. 9 is a side view of the leg unit of FIG. 7.

This application is a continuation-in-part of my application D. 4,017 filed Sept. 26, 1966, for Furniture Support, and now abandoned.

I claim:

The ornamental design for a leg unit, as shown and described,
